Filed Oct. 14, 1969, Ser. No. 19,550

Term of patent 14 years

Int. Cl. D7—04

U.S. Cl. D81—10

Fig. 1.

Fig. 2.

Fig. 3.

Fig. 4.

FIG. 1 is a front perspective view of a toaster shell embodying our new design;

FIG. 2 is a top plan view thereof;

FIG. 3 is a right side elevational view thereof; and

FIG. 4 is a sectional view taken along line 4—4 of FIG. 2.

The characteristic feature of our design resides in the substantially rectangular control support portion which is positioned centrally on the side wall of the toaster shell and the control knob mounted on the support portion, the diameter of the knob occupying a substantial part of the vertical dimension of the support portion.

We claim:

The ornamental design for a toaster shell, as shown and described.
